UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

SWITCH.

Application filed April 18, 1919. Serial No. 291,050.

To all whom it may concern:

Be it known that I, NEWMAN H. HOLLAND, a subject of the King of Great Britain, and a resident of West Orange, Essex County, New Jersey, have invented a new and useful Improvement in Switches, of which the following is a description.

This invention relates to switches and more particularly to switches for controlling a plurality of circuits and designed for use primarily in connection with electrically controlled dictating machines or business phonographs.

In dictating machines the record support is usually rotated by means of a motor and is started and stopped by a mechanical clutch, the device utilized for actuating the clutch being controlled by the transcriber or operator, as she or he desires to start or stop the reproduction of sound or matter dictated, my means of a switch.

One object of the invention is to provide an improved switch especially designed to control the starting and stopping of a dictating machine which requires very little attention on the part of the transcriber or operator, which can be operated by a movement like that used to actuate a typewriter key and which yields to the same kind of touch, like movements being used either to start or stop the machine.

Another object of the invention is to provide a switch which automatically controls one circuit and then another alternately upon successive actuations.

The invention consists further in details of construction and combination of parts hereinafter more particularly described and claimed.

In the accompanying drawing which forms a part of the specification the single figure is an elevation of a preferred form of switch in accordance with the present invention.

The improved switch embodying the present invention comprises a suitable casing 35 interiorly of and upon the bottom of which is secured a block 36 of insulating material. Attached to the block 36 are spaced contacts 37 and 38 having their adjacent ends upturned as indicated at 39. To the inside of opposite vertical sides of the casing are secured blocks 40 and 41 of in-

sulating material having secured thereto leaf-spring contacts 42 and 43 having portions lying in substantially the same horizontal plane, spaced from each other, arranged above and parallel with the contacts 37 and 38 respectively and adapted to be moved into engagement therewith, the contacts 42 and 43 tending normally by reason of their inherent resiliency to move out of engagement with the fixed contacts 37 and 38.

The casing 35 is provided with enlargements 44 and 45 arranged in vertical alignment and having aligned vertical openings receiving a plunger or actuating member 46 adapted to reciprocate therein. This plunger at its intermediate portion is provided with a cross-head 47 secured thereto by means of a set screw 48. A coil spring or similar means 49 encircling the plunger is interposed between the cross-head 47 and the enlargement 45 and tends normally to hold the plunger elevated with the cross-head in engagement with the lower end of the enlargement 44 as indicated at 50. The cross-head 47 is guided by and adapted to slide over surface 51 upon the casing.

Means is provided for alternately connecting the contacts of one circuit and then another automatically upon successive actuation of the plunger, the plunger being arranged to reciprocate in a direction at right angles to the contacts. In the present instance this means comprises a star wheel 52 preferably of insulating material and rotatably mounted upon the cross-head 47 by means of a pivot screw 53 on an axis lying in a vertical plane extending between the contacts 42 and 43. The star wheel comprises corners 54, 55 etc. which engage the contacts 42 and 43 when the plunger is actuated. Secured to the star wheel and interposed between the latter and the cross-head, is a ratchet 56 engaged by a spring-pressed pawl 57 to hold the star wheel against movement in one direction especially when it engages contact 43 and adapted to be rotated with the star wheel step-by-step, upon movement of the plunger 46, by suitable means, such as a spring-pressed pawl 58 mounted upon the casing. A spring arm 59 secured to the interior of the casing frictionally engages the star

wheel to hold the same steady and in position when advanced. In the form of the invention herein illustrated the spring 49 tends to keep the star wheel out of engagement with the contacts.

In order to actuate the plunger a lever 60 arranged like a typewriter key and pivoted at 61 extends over one end of the plunger and has an end 62 which is adapted to be tapped or touched by the operator for depressing the plunger.

To prevent the lever 60 from being displaced by the upward movement of the plunger, the former is provided on the side 15 of the pivot 61 remote from the end 62 with a downwardly extending portion 63 constituting a stop, adapted to engage the casing 35 and limiting the upward movement of the lever.

Reference characters 66 and 67 represent the conductors of one of the circuits controlled by the switch, these conductors being respectively connected to the contacts 43 and 38; while reference characters 68 25 and 69 represent conductors of another circuit controlled by the switch, such conductors being respectively connected to the contacts 37 and 42.

The operation of the form of my invention herein disclosed is as follows:

When it is desired to close the circuit of conductors 66 and 67, the parts being in the position shown in the figure, the lever 60 is depressed, moving the plunger with 35 the star wheel downwardly, the corner 54 of the star wheel engaging the contact 43 and closing its circuit. When the lever 60 is released the coil spring 49 elevates the cross-head and plunger, moving the star 40 wheel out of engagement with contact 43. As the star wheel moves upwardly the pawl 58 engages the ratchet 56, causes the rotation of the star wheel in a clockwise direction, looking at the drawing, and places 45 the corner 54 in such position that upon the next succeeding actuation of the lever 60 the corner 54 will move the contact 42 into engagement with the contact 37 thereby closing the circuit of conductors 68 and 50 69. To prevent the star wheel from slipping or moving when engaging contact 42 the latter is provided with a projection or abutment 72 with which it engages to keep it in position. When the lever 60 is again 55 released the plunger is elevated and the star wheel is moved clockwise another step, bringing the corner 55 into the position formerly occupied by the corner 54 shown in the drawing so that upon the next succeeding actuation the corner 55 moves into engagement with the contact 43 and closes 60 the circuit of conductor 66 and 67 as first described.

In order to prevent the star wheel from accidentally actuating both sets of con-

tacts at the same time should the star wheel be incompletely advanced, a stop 73 is interposed between the sets of contacts so that in case the star wheel is depressed with a corner at an intermediate point between the contacts it will engage the stop and prevent the closing of either or both circuits.

The circuits of conductors 66 and 67 and of conductors 68 and 69 may be respectively employed to control the starting and stopping of a dictating machine. If these circuits are so employed, it will be seen that if the lever 60 has been depressed to close the circuit of conductors 66 and 67 to thereby effect the starting of the dictating machine, the next depression of this lever will effect the closing of the circuit of conductors 68 and 69 to thereby effect the stopping of the machine.

The present invention provides a single 85 actuating device to control both circuits. The parts are so arranged and mounted that the lever 60 can be depressed by very little effort on the part of the operator and with the same kind of touch as is used on a typewriter. The automatic means or star wheel provides a construction requiring very little thought or attention because upon succeeding actuations first one circuit and then the other is closed automatically.

It is to be understood that the invention is not limited to the embodiments and features specifically shown and described herein but that such embodiments and features are subject to changes and modifications 100 without any departure from the spirit of the invention.

Having now described the invention, what is claimed as new and what it is desired to protect by Letters Patent of the 105 United States is as follows:

1. In a switch, contacts for a plurality of circuits, an actuating device comprising a member mounted for bodily movement towards and away from said contacts upon each actuation of said device and also for rotary movement, means for effecting a rotary movement of said member upon each actuation of said device, and means constantly tending to hold said member in a position 110 out of engagement with all of said contacts, the arrangement being such that upon successive actuations of said device such member will engage and disengage only a contact of one of said circuits and then only 115 a contact of another of said circuits to thereby effect the closing and opening of the respective circuits, substantially as described.

2. In a switch, contacts for a plurality of circuits, the contacts of each circuit being 120 movable into engagement with each other to close a circuit, and an actuating device adapted upon successive movements thereof to a given position to alternately engage 125 and move to circuit-closing position only a 130

contact of one circuit and then only a contact of the other circuit, said device being biased to a position out of engagement with all of said contacts, substantially as described.

3. In a switch, contacts for a plurality of circuits adjacent to and spaced from each other and arranged substantially in the same plane, the contacts of each circuit being movable into engagement with each other, and actuating means unattached to all of said contacts and adapted upon successive movements thereof to a given position to alternately connect the contacts of one of said circuits and then of another, said means being biased to a position out of engagement with all of said contacts, substantially as described.

4. In a switch, contacts for a plurality of circuits, an actuating member and means movable with said member and adapted upon successive movements of said member to a given position to alternately engage only a contact of one of said circuits and then only a contact of another, said means being biased to a position out of engagement with all of said contacts, substantially as described.

5. In a switch, contacts for a plurality of circuits, an actuating member, means movably mounted on said member for affecting only the contacts of one circuit and then only the contacts of the other circuit upon successive actuations of said member and means for imparting movement to said first means relatively to said member upon said actuations, said means being moved towards and away from said contacts upon each actuation of said member and being biased to a position out of engagement with all of said contacts, substantially as described.

6. In a switch, contacts for a plurality of circuits, an actuating member, means movably mounted on said member for connecting the contacts of one circuit and then the other upon successive actuations of said member, and means for imparting movement to said movably mounted means relatively to said member upon said actuations, said movably mounted means being biased to a position out of engagement with all of said contacts, substantially as described.

7. In a switch, contacts for a plurality of circuits, a member movable in opposite directions to respectively effect the connection and disconnection of said contacts and means movably mounted on said member and adapted to connect the contacts of one circuit and then the other upon successive movements of said member in the same direction, said means being biased to a position out of engagement with all of said contacts, substantially as described.

8. In a switch, contacts for a plurality of circuits in spaced relation to each other, a

reciprocating member, means rotatably mounted upon said member on an axis lying substantially in a plane between said contacts and means for imparting movement to said rotatable means whereby the latter is adapted to alternately engage a contact of one circuit and then of the other upon successive actuations of said member, said rotatable means being biased to a position out of engagement with all of said contacts, substantially as described.

9. In a switch, contacts for a plurality of circuits, a star wheel mounted for rotary movement and also for bodily movement towards and away from said contacts, said star wheel being adapted upon successive movements thereof towards and away from said contacts, to first engage and disengage only a contact of one of said circuits and to then engage and disengage only a contact of the other of said circuits, means for actuating said wheel, and means constantly tending to maintain said wheel in a position out of engagement with all of said contacts, substantially as described.

10. In a switch, contacts for a plurality of circuits, a member movable in opposite directions, a star wheel rotatably mounted upon said member and adapted to alternately engage a contact of one circuit and then of the other, means for automatically imparting a step-by-step movement to said wheel upon movement of said member and means tending to maintain said member and wheel in a given position out of engagement with all of said contacts, substantially as described.

11. In a switch, sets of contacts for a plurality of circuits in spaced relation to each other, a member movable relatively to said contacts, means rotatably mounted upon said member, means for imparting movement to said rotatable means whereby said rotatable means is adapted to alternately engage a contact of one circuit and then of the other and a stop interposed between said sets of contacts to prevent said rotatable means from engaging said contacts should the former be depressed prematurely, substantially as described.

12. In a switch, contacts for a plurality of circuits, an actuating member movable relatively to said contacts, means rotatably mounted on said member for engaging only a contact of one circuit and then only a contact of the other upon successive actuations of said member, means for rotating said first means and means to prevent movement of said rotatable means when engaging said contacts, said rotatably mounted means being biased to a position out of engagement with all of said contacts, substantially as described.

13. In a switch, contacts for a plurality of circuits, a member movable relative to

said contacts, means rotatably mounted on said member and adapted to alternately engage a contact of one circuit and then of the other, means for automatically imparting a step-by-step movement to said rotatable means upon movement of said member and means frictionally engaging said rotatable means, said rotatably mounted means being biased to a position out of engagement with all of said contacts, substantially as described.

14. In a switch, a casing, contacts for a plurality of circuits arranged horizontally in the lower portion of said casing, a member adapted to reciprocate vertically and provided with a head guided by a portion of the casing, a star wheel rotatably mounted upon said head above said contacts, a

spring tending to maintain said star wheel and reciprocating member in elevated position out of engagement with said contacts, a lever pivoted to said casing and overlying one end of said member for actuating the same, a ratchet wheel secured to said star wheel, a pawl pivoted to a portion of the casing and adapted to engage said ratchet wheel whereby said star wheel is advanced step-by-step upon the reciprocating of said member so that the former will alternately engage a contact of one circuit and then of the other, and means to prevent movement of the wheel when engaging said contacts, substantially as described.

This specification signed this 8th day of April, 1919.

NEWMAN H. HOLLAND.
